CLAIM

The ornamental design for an LED light up pickleball, as shown and described.

DESCRIPTION

FIG. 1 is a front perspective view of an LED light up pickleball, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded top view thereof;

FIG. 9 is an A-A cross sectional view of FIG. 5; and,

FIG. 10 is a B-B cross sectional view of FIG. 6.

The broken lines in the drawings illustrate the portions of the LED light up pickleball, which form no part of the claimed design.
